UNITED STATES PATENT OFFICE.

FRANCIS H. BUZZACOTT, OF CHICAGO, ILLINOIS.

DESIGN FOR A RANGE-END.

SPECIFICATION forming part of Design No. 34,412, dated April 23, 1901.

Application filed March 18, 1901. Serial No. 51,780. Term of patent 7 years.

To all whom it may concern:

Be it known that I, FRANCIS H. BUZZACOTT, a citizen of the United States, residing at Chicago, in the county of Cook and State of Illinois, have invented and produced a new and original Design for a Range-End, of which the following is a specification, reference being had to the accompanying drawings, forming a part hereof.

Figure 1 is an upper edge view of a range-end of my new and original design; Fig. 2, a view in outer face elevation of the same; Fig. 3, an end view of the same; Fig. 4, an inner face view of the same, and Fig. 5 a vertical section taken as indicated at line 5 of Fig. 4.

As shown in the drawings, the leading or material feature of my design consists in a plate A, having a substantially flat outer surface, a depressed upper margin a therefor,

inner face vertical ribs a' a² a³, the ribs a' a³ being in effect inturned flanges, a recess a⁴ near the upper end of the flange or rib a' for receiving a fire-door lug, horizontal ribs a⁵ crossing the ribs a², and a boss a⁶ at the base of said flange a' for receiving a pivot of the fire-door.

Having described my invention, what I claim as new, and desire to secure by Letters Patent, is—

The design for a range-end, as herein shown and described.

In testimony whereof I have signed my name to this specification in the presence of two subscribing witnesses.

FRANCIS H. BUZZACOTT.
